UNITED STATES PATENT OFFICE.

FRANK S. MANTON, OF PROVIDENCE, RHODE ISLAND.

DESIGN FOR A CAPSTAN.

SPECIFICATION forming part of Design No. 32,959, dated July 17, 1900.

Application filed June 9, 1900. Serial No. 19,783. Term of patent 14 years.

To all whom it may concern:

Be it known that I, FRANK S. MANTON, a citizen of the United States, residing at Providence, in the county of Providence and State 5 of Rhode Island, have invented and produced a new and original Design for a Capstan, of which the following is a specification, reference being had to the accompanying drawings, forming a part thereof.

Figure 1 is a plan view of a capstan, showing my new design; and Figs. 2 and 3 are side elevations.

As shown in the drawings, the leading or material feature of my design consists of a 5 hollow driving-head *h*, extending transversely

across the top of the capstan, a barrel *b* having its sides curved inwardly between its tip and bottom edges.

Having thus fully described my invention, what I claim as new, and desire to secure by 20 Letters Patent, is—

The design for a capstan as herein shown and described.

In testimony whereof I have signed my name to this specification in the presence of 25 two subscribing witnesses.

FRANK S. MANTON.
